EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

DESIGN FOR A SEAT END.

No. 39,630.

Specification for Design.

Patented Oct. 20, 1908.

Application filed July 24, 1908. Serial No. 445,288. Term of patent 7 years.

To all whom it may concern:

Be it known that I, EDWARD G. BUDD, a citizen of the United States, residing at Philadelphia, in the county of Philadelphia and State of Pennsylvania, have invented a new, original, and ornamental Design for Seat Ends, of which the following is a specification, reference being had to the accompanying drawing, forming a part thereof.

The figure is a plan view of a seat-end showing my new design.

I claim:
The original design for a seat-end, as shown.

EDWARD G. BUDD.
